APPARATUS FOR FEEDING AND ALIGNING SHEET MATERIAL

Application filed January 23, 1931. Serial No. 510,689.

My invention relates to feeding and aligning sheet material, as for the purpose of presenting it properly to trimming and cutting saws, and the like. The invention is especially advantageous for dealing with insulation building board, homogeneous hardwood board, paper, wood, and fiber pulp board, veneers, and other such materials; and I have hereinafter described and explained it with special reference to this use. Various advantages that can be realized through the invention will become apparent to those skilled in the art from the description hereinafter.

In the drawings, Fig. I is a plan view of an apparatus conveniently adapted for and embodying the invention.

Fig. II is a side elevation, from the front of Fig. I, showing the apparatus with provisions for delivering sheets thereto from above, as from the discharge of a drier.

Fig. III is a fragmentary sectional view, taken as indicated by the line and arrows III-III in Fig. I.

In Figs. I and II, my feeding and aligning apparatus 4 is shown arranged like a table in front of a trimming and cutting equipment 5, comprising saws 6, 6, 6 driven by individual electric motors 7, 7, 7 and located between pairs of suitably driven entrance and exit feed rolls 8, 8 and 9, 9, which definitely control the sheet S during the action of the saws thereon. My apparatus 4 acts to assure presentation of the sheet S to the entrance rolls 8, 8 in proper definite alignment under all circumstances.

As shown in Fig. I, my feeding and aligning table 4 comprises a stop 10 for the edge of the fiber sheet S, associated with means or devices 11 for sustaining the sheet and feeding it along, and concurrently pushing or pressing it against the stop 10. To minimize friction with the edge of the sheet S, the stop 10 may consist of a series or line of upright rolls or rollers 12, preferably with stop walls 13 between them to prevent the leading corner of a sheet S from catching and "blocking" against a roll 12. The feeding means 11 here shown consists of a multiplicity of rotary discs lying in planes inclined somewhat to the stop 10, and revolving toward the stop,

i.e., counter-clockwise in Figs. I and II. The discs 11 are mounted, at suitable intervals, on a series of shafts 14 extending oblique to the stop 10, and themselves suitably spaced apart. Thus each shaft 14 with its discs 11 in effect constitutes a roll oblique to the stop 10; however, the multiplicity of discs 11 presents important advantages over a series of mere ordinary rolls, as will appear hereinafter. The roll formed by the discs 11 on each shaft 14 is adapted to yield in the axial direction, by virtue of the axially or laterally yielding capacity of the discs, as hereinafter explained. As shown in Fig. I, the discs 11 on the several shafts 14 are arranged in rows lengthwise of the table 4, paralleling the stop 10.

As the revolving discs 11 carry the sheet S along, they also press or crowd it over against the stop 10, thus bringing it to a definite position of alignment with respect to the whole apparatus. At the front of the table 4 is a feed device for passing the sheet S along to the cutting and trimming apparatus 5 while definitely maintaining its alignment, consisting of cooperating pairs of feed discs 15, 15, of the same resilient character as the discs 11, revolving in planes parallel to the stop 10, and mounted on shafts 16, 16 extending at right angles to the stop 10. As shown in Figs. I and II, the lower shaft 16 is driven by a sprocket and chain connection 16a to the axis of the lower entrance roll 8 of the cutting and trimming apparatus 5. The ends of the upper shaft 16 are journalled in blocks 16b in vertical ways 16c on the machine frame, and adjusting screws 16d serve to vary the pressure between the discs 15, 15 according to the thickness and character of the sheet material S.

As shown in Figs. II, and III, the feed shafts 14 are mounted in bearings 17 attached to the side members 18 of the machine frame. The stop rollers 12 are mounted on vertical axes (studs or spindles) 19 secured to the horizontal flanges of angle bars 20, and project through openings in the vertical flanges of these angle bars 20,—which vertical flanges form the stop walls 13 between the rollers. The front ends of the feed shafts 14 are con-

nected together by a series of chain and sprocket connections 21 and are driven by an electric motor 22, through reduction gearing 23 and a chain and sprocket connection 24 to the front or left-hand shaft 14 (Figs. I and II). As shown in Fig. III, the feed discs 11 are mounted on the shafts 14 between flanges 25, 26 suitably secured to the shafts. Preferably, the discs 11 are of a resiliently yielding material that will adhere well by friction to a fiber sheet S. The material that I prefer for this purpose is sponge rubber such as is used for the cushion backs of rubber stamps: it comes in sheets an inch thick from which the discs 11 can easily be cut. They can be cemented or vulcanized to the flanges 25, 26, or even simply clamped between them and held from turning by mere friction.

Fig. II shows a plurality of roll racks 30 arranged to feed sheets upon the table 4, obliquely downward and in the direction of rotation of the discs 11. These roll racks 30 may constitute the delivery of a drier or other apparatus in which sheets travel in superposition. The leading edges of the sheets from the various roll racks 30 strike the table 4 at various positions in its length, and travel to the left, so that the sheets gradually come down flat on the table. Fig. II shows one sheet S in the act of doing this,—its leading edge being at s. In the intervals between the rows or "rolls" of discs 11 on the several shafts 14, means are provided for receiving a downcoming (leading) sheet edge S when it first reaches the table 4 and guiding or carrying it along to the first row of discs 11 in front of it, substantially or approximately tangential to the peripheries of the discs 11: otherwise, a sheet might just happen to strike the table 4 between adjacent transverse rows of discs, and slip downward between them. For this purpose, a number of parallel belts 32 are shown extending lengthwise of the table 4 between its longitudinal rows of discs 11. These belts 32 extend around pulleys 33 on shafts 34, 34 and 35 at the left and right of the machine, respectively. The upper runs of the belts 32 are supported by rolls 36, 36, arranged in alternation with the shafts 14 and their discs 11. As shown in Fig. I, there are two sets or series of the rolls 36, 36 in the width of the table 4, with their axes or trunnions 37 mounted in bearings on the longitudinal frame members, and likewise two of the shafts 34, 34. Corresponding rolls 36, 36 in the two sets are offset relative to one another, as required by the inclination of the shafts 14, and the two shafts 34, 34 are also offset.

The revolving discs 11 carry the sheet S along toward the left (Figs. I and II) continuously, and at the same time push or crowd it over against the stop 10, thereby eventually bringing it from a skew position such as shown in full lines in Fig. I to a position of definite alignment such as shown in dot and

dash lines. After the edge of the sheet S comes in contact with the stop 10, the margins of the discs 11 yield and deflect sidewise (axially) under further thrust against the stop, as shown in Fig. III, the discs being sufficiently resilient (and at the same time adhesive to the sheet) to propel the sheet forward and give sideways at their upper peripheries while their lower peripheries are returning to the normal plane of the disc. 70

Having thus described my invention, I claim:

1. Apparatus of the character described for feeding and aligning sheet material, comprising an aligning stop for the edge of the material, and a series of axially yielding rotary feed rolls extending oblique to said stop and revolving toward it, so as to press the material against the stop as they carry it along, but yielding in the axial direction after 80 the material comes against the stop.

2. Apparatus of the character described for feeding and aligning sheet material, comprising an aligning stop for the edge of the material, and a multiplicity of axially or laterally yielding resilient edged rotary feed discs revolving toward the stop in planes inclined thereto, so as to press the material against the stop as they carry it along, but yielding and deflecting sidewise after the 90 material comes against the stop.

3. Apparatus of the character described for feeding and aligning sheet material, comprising a line of stop rolls for engaging the edge of the material, and a multiplicity of 100 axially or laterally yielding adherent edged rotary feed discs revolving toward the series of stop rolls in planes inclined thereto, so as to press the material against the stop rolls as they carry it along, but yielding and deflecting sidewise after the material comes against the stop.

4. Apparatus of the character described for feeding and aligning sheet material, comprising an aligning stop for the edge of the material, a series of shafts extending to one side of said stop oblique thereto, and revolving toward it, and a plurality of resilient feed discs on each shaft for carrying the material and pressing it against the stop, but yielding and deflecting sidewise after the material comes against the stop. 110

5. Apparatus of the character described for feeding and aligning sheet material, comprising an aligning stop for the edge of the material, a series of shafts extending to one side of said stop oblique thereto, and revolving toward it, and a plurality of feed discs of sponge rubber on each shaft for carrying the material and pressing it against the stop. 120

6. Apparatus of the character described for feeding and aligning sheet material, comprising an aligning stop for the edge of the material, rows of rotary feed discs at one side of said stop revolving toward it in planes in- 130

clined to it, so as to press the material against the stop as they carry it along, and movable belts extending between the rows of discs.

7. Apparatus of the character described for feeding and aligning sheet material, comprising an aligning stop for the edge of the material, a series of shafts extending to one side of said stop oblique thereto, and revolving toward it, rows of feed discs on said shafts for carrying the material and pressing it against the stop, movable belts extending between the rows of discs, and series of supporting rolls for said belts between said shafts, the rolls of one series being offset relative to the corresponding rolls of the adjacent series.

8. Apparatus of the character described for feeding and aligning sheet material, comprising an aligning stop for the edge of the material, a series of rotary feed rolls extending oblique to said stop and revolving toward it, means for feeding sheets from above obliquely down upon said series of rolls in their direction of revolution, and moving means for receiving the leading downcoming sheet edges between rolls and carrying them tangentially to the rolls.

9. Apparatus of the character described for feeding and aligning sheet material, comprising a table of rows of rotary feed discs, means for feeding sheets from above obliquely down upon said table of discs, and movable belts extending between the rows of discs for receiving downcoming sheet edges between adjacent disc rows and carrying them tangentially to the discs.

10. Apparatus of the character described for feeding and aligning sheet material, comprising an aligning stop for the edge of the material, a table of rows of rotary feed discs revolving toward the stop in planes inclined thereto, means for feeding sheets from above obliquely down upon said table of discs, and movable belts extending between the rows of discs for receiving downcoming sheet edges between adjacent disc rows and carrying them tangentially to the discs.

In testimony whereof, I have hereunto signed my name at Trenton, New Jersey, this

50 19 day of January, 1931.

FRANCIS S. FARLEY.
